UNITED STATES PATENT OFFICE.

IVERT LARSEN, OF CHICAGO, ILLINOIS.

DESIGN FOR A BADGE.

SPECIFICATION forming part of Design No. 23,493, dated July 24, 1894.

Application filed June 1, 1894. Serial No. 513,211. Term of patent 7 years.

To all whom it may concern:

Be it known that I, IVERT LARSEN, of Chicago, Cook county, Illinois, have invented and produced a new and useful Design for Badges, 5 of which the following is a specification.

The accompanying drawing is a face view of a badge showing my design.

The leading feature of the design is a star-shaped badge, A, having a circle, B, in its 10 body, and game and fish, C, inside the circle.

As shown, there are also small stars on the circle around the game or fish.

I claim—

The design for a badge, substantially as herein shown and described.

IVERT LARSEN.
